SWITCH OF THE CROSSBAR TYPE

John Wicks, Biloxi, Miss., assignor to Automatic Electric Laboratories, Inc., Chicago, Ill., a corporation of Delaware

Application February 19, 1948, Serial No. 9,357

8 Claims. (Cl. 179—27.54)

1

The present invention relates in general to switching apparatus, and more particularly to improvements in switching apparatus of the cross-bar type for use in automatic and semi-automatic telephone systems.

Cross-bar switches are well known in the art and comprise essentially a plurality of contact sets arranged in intersecting horizontal and vertical rows, together with two groups of related intersecting operating bars so arranged that the actuation of one bar in each group causes the operation of a contact set at the point of intersection of the two actuated bars. Individual magnets have generally been provided for actuating each of the operating bars, although in some instances the operating bars of a group have been actuated in a step-by-step manner by a ratchet mechanism common to the group. A particular type of cross-bar switch provides an arrangement wherein the number of operating bars of one group is one-half the number of the operating bars of the other group. In such an arrangement, the operation of a bar of the first, or smaller, group in either of opposite directions causes the selection of one or another related row of contact sets for operation by a single movement of a bar of the second, or larger, group. It is to this latter type of cross-bar switch that an embodiment of the present invention is directed.

An object of the invention is to provide an improved cross-bar switch which is economical to manufacture and simple to maintain.

Another object of the invention is to reduce in a new and novel manner the number of control elements required in a cross-bar switch.

A feature of the invention resides in the improved arrangement wherein a common cross-bar shaft controls the movements of a group of operating bars in a new and novel manner.

Another feature of the invention relates to the provision of a step-by-step mechanism for controlling the rotative movement of a common cross-bar shaft and means for thereafter operating the rotated shaft longitudinally in either direction.

There are other objects and features of the invention having to do for the most part with the details in carrying out the foregoing. The various objects and features of the invention will be understood best upon a further perusal of the specification taken in conjunction with the accompanying drawing in which:

Fig. 1 shows a perspective view of a cross-bar switch to which the present invention has been applied;

2

Fig. 2 shows the method of mounting selecting fingers on the vertical cross-bars; and

Fig. 3 is a sectional view taken along the line A—A in Fig. 1, showing a method of slidably mounting the ratchet wheel on the common set rod.

Referring now to Fig. 1, the cross-bar switch therein disclosed is shown in diagrammatic form rather than in elevation in order to reduce Fig. 1 to the simplest possible form, it being considered unnecessary for the purpose of illustrating the application of the present invention to detail such well-known structural devices as a suitable framework, bearings and mountings for the various cross-bars and common shafts, and the like. It should be understood at this time that the cross-bar switch in Fig. 1 is representative of cross-bar switches in general and that the present invention is equally applicable to other forms and arrangements of cross-bar switches. It should also be understood that while the cross-bar switch in Fig. 1 discloses only one contact set at the intersections of the vertical and horizontal rows of contact springs, a plurality of contact sets can readily be employed.

The cross-bar switch shown in Fig. 1 has four horizontal bars 101, 102, 103, 104 and two vertical bars 120 and 125. Each of these cross-bars is rotatably pivoted in any well-known type of bearing (not shown), the bearings for each bar being rigidly mounted at two or more points on a suitable framework (partly shown). Associated with each horizontal bar is horizontal contact spring assembly 130, and associated with each vertical bar are two vertical rows of contact springs 141 and 142. Contacts are fitted at the intersecting, or cross, points of these horizontal and vertical rows of contact springs in order that electrical connections may be established between the contact springs as controlled by the operation of the vertical and horizontal bars.

Vertical bars 120, 125 each have means for selecting one or the other of the related vertical rows of contact springs 141, 142, and horizontal bars 101, 102, 103, 104 each have means for operating a selected contact set at the intersection of the horizontal bar with a vertical bar. It is, therefore, evident that only one-half the number of vertical bars with respect to the horizontal bars are required. It should be understood, however, that the switch is not limited to the number of cross bars shown in Fig. 1, but may be fitted with any required number of horizontal bars and the corresponding number of vertical bars. The horizontal bars in Fig. 1 are shown broken to indicate this flexibility.

The contact spring selecting means associated with each vertical bar comprises one selecting finger 121 for each set of contact springs 141 and 142 accessible to the vertical bar. These fingers 121 are located opposite the related rows of contact springs 141, 142, and are attached to the vertical bars in the well-known manner shown in Fig. 2. When a vertical bar is rotated in a counter-clockwise direction, the fingers 121 of the vertical bar are correspondingly moved to the left underneath the shoulders 143 of the contact springs 141. In a similar manner, when a vertical bar is rotated in a clockwise direction, the fingers 121 of the vertical bar are correspondingly moved to the right underneath the shoulders 144 of the contact springs 142.

The contact operating means associated with each horizontal bar comprises a shoulder cut-out 122 opposite each vertical bar, in which cut-outs the free ends of the respective selecting fingers 121 operate. The left-hand vertical face of cut-out 122 limits the left-hand travel of finger 121, and the right-hand vertical face of cut-out 122 correspondingly limits the right-hand travel of finger 121. When a selecting finger is in the normal, or neutral, position it rests on the related cut-out 122 midway between and clearing the shoulders 143, 144 of the contact springs 141 and 142. Rigidly attached to and forming a part of each horizontal bar 101, 102, 103, 104 is a lug 123 for providing means whereby the front member of the horizontal bar may be lifted in a vertical plane in the manner to be subsequently described. When a horizontal bar is lifted through the medium of lug 123, the cut-outs 122 of the horizontal bar are correspondingly moved upwardly and, consequently, a selecting finger 121 resting underneath either shoulder 143 of a contact spring 141 or shoulder 144 of a contact spring 142 at the intersection of the horizontal bar with a vertical bar causes the related contact spring 141 or 142 to be raised thereby to make electrical contact with the related horizontal contact spring 130. The horizontal contact springs 130 are fixedly mounted and do not move when a contact spring 141 or 142 is pressed upwardly.

To rotate a vertical cross-bar in either direction thereby to select a row of contact springs 141 or 142, a common horizontal shaft, or set rod, 100 is provided. This set rod 100 is journaled in suitable bearings (not shown) in a horizontal plane with respect to the vertical cross-bars, the bearings permitting rotative and longitudinal movements of the set rod. Set rod 100 is provided with a plurality of spirally arranged pins 105, one for each vertical cross-bar. The pins 105 are rigidly mounted on set rod 100, and are so located that one pin at a time, and only one pin, will engage the open end of lever 124 of the respective vertical cross-bar. Set rod 100 is rotated in a step-by-step manner for selecting a particular vertical cross-bar, by means of a magnet 107 operating a stepping pawl 108 for the ratchet wheel 106.

While set rod 100 is rotative with ratchet wheel 106, ratchet wheel 106 is slidably mounted on set rod 100 in order that set rod 100 may be shifted longitudinally in either direction without correspondingly shifting ratchet wheel 106. A two-membered bracket 119 (shown in Figs. 1 and 3) attached to the framework of the switch in any suitable manner retains ratchet wheel 106 in position with respect to magnet 107 and stepping pawl 108, clearance holes in the two members of bracket 119 permitting set rod 100 to be shifted

to the left or right without interference. A key 126 (Fig. 3) affixed to set rod 100 and passing through a clearance slot in ratchet wheel 106 provides means whereby ratchet wheel 106 may cause the rotation of set rod 100 and whereby set rod 100 may be shifted to the left or right without affecting ratchet wheel 106.

After a vertical cross-bar such as 120 has been selected by the rotation of set rod 100 to the position where pin 105 at the left-hand end of set rod 100 engages the open end of lever 124 attached to vertical bar 120, set rod 100 is then operated longitudinally in one direction or the other dependent upon whether the fingers 121 of vertical bar 120 are to select contact springs 141 or contact springs 142. The longitudinal movement of set rod 100 to the left is controlled by magnet 109, and the longitudinal movement to the right by magnet 110. Both of these magnets are fixedly attached to the framework of the switch in any well-known manner, and either magnet may operate armature 111. Attached to armature 111 at the center point is a member 112, the free end of which rests between collars 113 and 114 fixedly attached to set rod 100 and rotatable therewith.

When magnet 109 is energized and attracts armature 111, the free end of member 112 correspondingly presses against collar 113 thereby forcing set rod 100 to the left against the increasing tension of helical spring 115 which is loosely mounted over set rod 100 between collar 113 and bracket 116 of the switch framework. A clearance hole in bracket 116 enables set rod 100 to move freely in bracket 116. Pin 105 at the left-hand end of set rod 100, therefore, operates lever 124 of vertical bar 120 to the left, the ball-like end of pin 105 and the rounded inside contour of the open end of lever 124 reducing friction between these two members to a minimum. The rotation of vertical bar 120 clockwise, as a result of set rod 100 being shifted to the left by the energization of magnet 109, causes the free ends of the selecting fingers 121 of vertical bar 120 to be moved to the right underneath the shoulders 144 of the respective contact springs 142, thereby selecting the respective contact springs 142.

When magnet 110 is energized and attracts armature 111, the free end of member 112 correspondingly presses against collar 114 thereby forcing set rod 100 to the right against the increasing tension of helical spring 117 which is loosely mounted on set rod 100 between collar 114 and bracket 118 of the switch framework. A clearance hole in bracket 118 enables set rod 100 to move freely in bracket 118. Pin 105 at the left-hand end of set rod 100, therefore, operates lever 124 of vertical bar 120 to the right, and the resulting counter-clockwise rotation of vertical bar 120 causes the free ends of the selecting fingers 121 of vertical bar 120 to be moved to the left underneath the shoulders 143 of the respective contact springs 141, thereby selecting the respective contact springs 141.

After a vertical cross-bar such as 120 has been rotated counter-clockwise or clockwise in order to cause the selection of the related row of contact springs 141 or the related row of contact springs 142 in the manner just described, one of the horizontal cross-bars 101, 102, 103 or 104 is lifted to cause the selected contact spring 141 or 142 at the intersection point of the lifted horizontal cross-bar with vertical bar 120 to make contact with the contact spring assembly

130 associated with the lifted horizontal cross-bar. A common shaft, or control rod, 150 is provided for lifting the horizontal cross-bars. This control rod 150 is journaled in suitable bearings (not shown), the bearings permitting rotative and longitudinal movements of the control rod. Control rod 150 is provided with a plurality of spirally arranged pins 151, one for each horizontal cross-bar, arranged in a similar manner to that previously described for set rod 100. Control rod 150 is rotated in a step-by-step manner for selecting a particular horizontal cross-bar, by means of a magnet 152 operating a stepping pawl 153 for the ratchet wheel 154.

In a similar manner to the arrangement of set rod 100, control rod 150 is rotative with ratchet wheel 154, and ratchet wheel 154 is slidably mounted on control rod 150 in order that control rod 150 may be shifted longitudinally without correspondingly shifting ratchet wheel 154. A two-membered bracket 155 (shown in Fig. 1) attached to the framework of the switch retains ratchet wheel 154 in position with respect to magnet 152 and stepping pawl 153 in a similar manner to that previously explained for ratchet wheel 106.

After a horizontal cross-bar such as 101 has been selected by the rotation of control rod 150 to the position where pin 151 near the upper end of control rod 150 engages lug 123 of horizontal bar 101, control rod 150 is then operated longitudinally in an upward direction through the energization of magnet 156. Armature 157 is attracted by magnet 156, and member 158 in contact with the under face of collar 159 (collar 159 being fixedly attached to control rod 150) correspondingly raises control rod 150 by forcing collar 159 upwardly against the increasing tension of helical spring 160. Helical spring 160 is loosely mounted over control rod 150 between collar 159 and bracket 161 of the switch framework, and is tensioned to cause member 158 to normally hold armature 157 in its retracted position. A clearance hole in bracket 161 enables control rod 150 to move freely in bracket 161.

The lifting of control rod 150 in the manner described in the preceding paragraph causes the uppermost pin 151 to raise lug 123 of horizontal bar 101. The horizontal face of the cut-out 122 nearest the left-hand end of horizontal bar 101, therefore, presses the outer end of finger 121 located near the top end of vertical bar 101 upwardly against the shoulder 143 of the related contact spring 141 or upwardly against the shoulder 144 of the related contact spring 142 dependent upon which of the two contact springs was previously selected by the setting of vertical bar 120. Either contact spring 141 or contact spring 142 is, consequently, raised thereby to make electrical contact with horizontal contact spring assembly 130 associated with horizontal bar 101.

The holding of horizontal bar 101 in the raised position by magnet 156 maintains the uppermost finger 121 of vertical bar 120 in the engaged position, although vertical bar 120 may be returned to its normal position by the release of set rod 100. The return of vertical bar 120 will place the rest of the selecting fingers 121 of vertical bar 120 in the center, or neutral, position in a well-known manner. The release of set rod 100 is accomplished by de-energizing either magnet 109 or magnet 110, as the case may be. Either helical spring 115 or spring 117 then causes either collar 115 or collar 116 to force

member 112 to the center position thereby to cause the retraction of armature 111. The normal tensions of springs 115 and 117 cause collars 113 and 114 to retain member 112 in the center position. The release of set rod 100 causes the left-hand pin 105 of set rod 100 to return vertical bar 120 to its normal, or neutral, position in an obvious manner.

The release of the established connection at 10 the intersection point of horizontal bar 101 with vertical bar 120 is accomplished by de-energizing magnet 156 now holding horizontal bar 101 in the raised position, thereby permitting helical spring 160 to cause collar 159 to force member 158 downwardly. Control rod 150, consequently, is returned to its lower position and armature 157 is retracted. The release of control rod 150 permits horizontal bar 101 to be returned to its lower, or normal, position by the spring action of either operated contact spring 141 or operated contact spring 142 (as the case may be). As horizontal bar 101 reaches its lower position, the left-hand shoulder 122 of horizontal bar 101 no longer exerts pressure on the engaged finger 121 of vertical bar 120, and this engaged finger 121 of vertical bar 120 is consequently, returned to its center, or neutral, position in a well-known manner.

Set rod 100 may be so arranged as to have a 30 normal, or home, position and after its release by the de-energization of either magnet 109 or magnet 110 (as the case may be) may be returned to the home position through any well-known means of automatically stepping magnet 35 197 until the home position is reached. Control rod 150 may also be similarly arranged to be automatically returned to a home position upon the de-energization of magnet 156.

While the present invention is disclosed in 40 connection with but a single form of cross-bar switch, it should be understood that the various features thereof could readily be applied to other forms of switch structures without departing from the spirit thereof, and that the present disclosure should only be considered as illustrative of one embodiment of the invention.

What is claimed is:

1. In a switch, two bars mounted adjacent each other in an intersecting plane, two sets of contacts at said intersection of said bars, one of said bars having means for selecting either of said contact sets, a shaft adjacent to said bars at an angle to said one bar and having means for engaging said one bar, means for rotating said shaft thereby to cause said shaft to engage said one bar, means for moving said shaft longitudinally in either of two directions, the moving of said shaft in one of said directions causing said selecting means of said one engaged bar to select one 50 of said contact sets, the moving of said shaft in said other direction causing said selecting means of said one engaged bar to select said other contact set, and means for causing said other bar to operate the selected contact set.

2. The switch claimed in claim 1 wherein said last means comprises a shaft adjacent to said bars at an angle to said other bar and having means for engaging said other bar, means for rotating said last shaft thereby to cause said last shaft to engage said other bar, and means for moving said last shaft longitudinally thereby to cause said other engaged bar to operate said selected contact set.

3. The switch claimed in claim 1 wherein said 75 means for moving said shaft longitudinally in

either of said two directions comprises two magnets, an armature common to both said magnets, and a lever attached to said armature and engaging said shaft, the operation of one of said magnets operating said armature thereby to cause said lever to move said shaft in one of said directions, the operation of said other magnet operating said armature thereby to cause said lever to move said shaft in said other direction.

4. In a switch, first and second groups of bars mounted adjacent each other in intersecting planes, two sets of contacts at each of the intersections of said bars, means individual to the respective bars of said first group for selecting one or the other of said contact sets at each of the intersections of said respective bars with the bars of said second group, a shaft adjacent to said two groups of bars at an angle to the bars of said first group and having means for engaging any one of the bars of said first group, means for rotating said shaft thereby to cause said shaft to engage one of said bars of said first group, means for thereafter moving said shaft longitudinally in either direction, the moving of said shaft in one of said directions causing said means of said one engaged bar to select one of said contact sets at each of the intersections of said one engaged bar with the bars of said second group, the moving of said shaft in said other direction causing said means of said one engaged bar to select said other contact sets at each of the intersections of said one engaged bar with the bars of said second group, and means for causing one of said bars of said second group to operate the selected contact set at the intersection of said one engaged bar of said first group with said one bar of said second group.

5. In a switch, the combination of a plurality of A bars each having contact conditioning means, a plurality of B bars each having contact operating means, said pluralities of bars arranged in intersecting rows, two contacts at each intersection point of said bars, the rotative movement of an A bar in one or another direction causing its contact conditioning means to correspondingly condition one or the other of said contacts at each intersection point of said one A bar with said B bars, the rotative movement of a B bar causing its contact operating means to operate the conditioned contact at the intersection point of said B bar with a rotated A bar, a shaft adjacent to said A bars and having means for engaging any one of said A bars, a step-by-step mechanism for rotating said shaft thereby to select one of said A bars, means for moving said shaft longitudinally in either direction to correspondingly rotate a selected A bar, a shaft adjacent to said B bars and having means for engaging any one of said B bars, a step-by-step mechanism for rotating said last shaft thereby to select one of said B bars, and means for moving said last shaft longitudinally to cause the rotation of a selected B bar.

6. In a cross-bar switch, horizontal and vertical bars, a first shaft common to said vertical bars and having means for selecting any one of said vertical bars, a second shaft common to said horizontal bars and having means for selecting any one of said horizontal bars, a selecting arm adjacent each horizontal bar on each vertical bar, a horizontal row of contacts individual to each horizontal bar and arranged in vertical

columns having a first and a second vertical column individual to each vertical bar, means for initially operating said first common shaft thereby to select one of said vertical bars, means for initially operating said second common shaft thereby to select one of said horizontal bars, means for selectively operating said first common shaft to selectively actuate said selected vertical thereby to cause the selecting arms thereon to select either said first column or said second column of contacts individual to said actuated vertical bar, means for further operating said second common shaft to actuate said selected horizontal bar, means responsive to said actuation of said selected horizontal bar for actuating the selecting arm of the actuated vertical bar adjacent said actuated horizontal bar, and means responsive to said actuation of said last mentioned selecting arm for operating the contact previously selected by said last mentioned selecting arm.

7. In a switch, the combination of a plurality of first bars, a plurality of second bars, said pluralities of bars arranged in intersecting planes, two sets of contacts at each intersection point of said first and second bars, contact conditioning means individually associated with each of said first bars, step-by-step controlled means for selecting any one of said first bars, means for rotating a selected first bar in one or the opposite direction thereby to cause its contact conditioning means to condition one or the other of said two contact sets at each intersection point of the selected first bar and said second bars, contact operating means individually associated with each of said second bars, step-by-step controlled means for selecting any one of said second bars, and means for rotating a selected second bar thereby to cause its contact operating means to operate the conditioned set of contacts at the intersection point of the selected second bar and a rotated first bar.

8. In a switch, two bars adjacent each other in an intersecting plane, two contacts associated with one of said bars at said intersection of said bars, said other bar having means for selecting either of said contacts, a shaft adapted for being operated in three different directions, said shaft having means for engaging said other bar, means for operating said shaft in one of said directions thereby to cause said engaging means of said shaft to engage said other bar, means for operating said shaft in a second of said directions thereby to cause said selecting means of said engaged other bar to select one of said contacts, and means for operating said shaft in the third of said directions thereby to cause said selecting means of said engaged other bar to select said other contact.

JOHN WICKS.
